UNITED STATES PATENT OFFICE

LOUIS H. GEBHART AND STANLEY G. WISE, OF DAYTON, OHIO, ASSIGNORS TO THE GEBHART FOLDING BOX COMPANY, OF DAYTON, OHIO, A CORPORATION OF OHIO

BOX

Application filed September 23, 1927. Serial No. 221,576.

Our invention relates to containers.

It is the object of our invention to provide a container of the automatic box type which may be shipped in flat knocked-down condition and held rigidly in such condition during shipment; and thereafter be capable of being broken into assembled position.

It is a further object to provide a box which will maintain itself in assembled position in relatively rigid condition due to the end flap of the end wall of the box having a serrated end engaging with a corresponding serrated reinforcing strip on the inside of the box, there being a space between the end of the reinforcing strip and the upturned end wall for receiving the overturned inwardly-disposed end of the end wall.

Referring to the drawings:

Figure 1 is a plan view of one end of the box as it is shipped flat in unbroken position;

Figure 2 is a section therethrough on the line 2—2;

Figure 3 is a similar view showing the position of the box when it is broken prior to opening and final assembly;

Figure 4 is a plan view of the end of the box in open condition prior to the folding inwardly of the corner folds and the elevating into a vertical position of the side walls;

Figure 5 is a top plan view of the box with the corner folds folded inwardly, the side walls in the vertical and the end wall in a vertical plane prior to the folding over of the serrated end of the end flap, which folds over the corner folds;

Figure 6 is a top plan view of the box in final folded condition;

Figure 7 is a section on the line 7—7 thereof;

Figure 8 is a plan view similar to Figure 4 showing a modified form of corner flap;

Figure 9 is an inside end elevation of the modified form of Figure 8 prior to the folding inwardly of the serrated end flap;

Figure 10 is a section on the line 10—10 of Figure 9.

Referring to the drawings in detail, 1 is the bottom of a box, 2 is a side wall and 3 and 4 designate the triangular halves of a corner flap, which is adapted to fold inwardly along

the score line 5. The corner flap is integrally connected along the score line 6 to the side wall 2 and the score line 7 to the end wall 8. The end wall is hinged along the score line 9 to the bottom 1. It is hinged along 55 the line 10 at the top thereof to an inwardly folding end flap 11 having a serrated edge 12.

This serrated edge is formed by the breaking away at 13 of the serrated end flap from a serrated reinforcing strip of which it is an 60 integral part until broken, such strip being designated 14 and having a serrated edge 15.

The box is shipped flat with the end flap 11 folded over the end wall 8 and the serrated edges 12 and 15 in abutting integral engagement but perforated to facilitate the rupture along the serrated edges. The strip 14 is pasted to the bottom to hold the end flap in 65 position, to reinforce the box and to strengthen the box during shipment.

When it is desired to assemble the box, the end flap and end wall are bent, as in Figure 3, causing a rupture along the perforated line. The end flap is then unfolded, the side walls are elevated so that the corner flaps 70 75 are bent inwardly, as will be seen in Figure 5, and then the end flap 11 is folded over and inwardly enclosing the corner flaps, so that the serrated edge 12 is inserted in the space 16 between the serrated edge 15 and the score 80 line 9.

These rough edges engaging with one another serve to hold the end flap in position, together with the fact that the end flap is 85 yieldingly held against the serrated edge 15 of the strip 14 by reason of its end being in the space 16 and pushed against the edge 15 by the expanding corner flaps, which provide a bellows-like expanding action. Thus, the box is held in firm position.

For clarity in Figure 7, the end flap 11 is 90 not shown in engagement with the bottom 1 and strip 14, but, in practice, that usually occurs, due to the expansion of the corner flaps.

In the modified form, the corner flap 17 95 is a non-folding flap hinged to the side wall 2 along the lines 6 but severed at 18 from the end wall. Otherwise, it is the same, and the construction and folding are the same. 100

It will be understood that we desire to comprehend within our invention such modifications as may be clearly embraced within the scope of our invention and claims.

5 Having thus fully described our invention, what we claim as new and desire to secure by Letters Patent is:

1. In a container, a bottom, side walls hinged thereto, corner flaps, and an end wall, 10 an end flap hinged to and overlying the end wall and having an overlapping serrated part attached to the bottom of the container, said end flap being adapted to be detached from the portion thereof attached to the bottom 15 of the container along a serrated line.
2. In a container, a bottom, side walls hinged thereto, corner flaps, and an end wall, an end flap hinged to and overlying the end wall and having an overlapping serrated part 20 attached to the bottom of the container, said end flap being adapted to be detached along a serrated line from the portion thereof attached to the bottom of the container, the line of detachment being removed from the 25 hinged line of the end wall with the bottom.
3. In a container, a bottom, side walls hinged thereto, end walls hinged thereto, corner flaps adapted to nest within said ends walls, a serrated reinforcing strip mounted 30 across the bottom adjacent the inside of the end wall but spaced therefrom, and an inwardly turned end torn from the serrated reinforcing strip thereby hinged to said end wall adapted to overlap the corner flaps, and 35 a serrated edge on said free end of the end flap.
4. In a container, a bottom, side walls, end walls and corner flaps hinged one to the other, and an inwardly turned end flap having 40 a portion overlapping the end wall and a portion of the bottom and attached to the bottom having a readily breakable serrated portion to permit of the severing of the major portion of the end flap from the portion overlapping the bottom.

45 In testimony whereof, we affix our signatures.

LOUIS H. GEBHART.
STANLEY G. WISE.
